METER PIT

Harold E. Cossen, Sheboygan, Wis., assignor to
Ametek, Inc., Sheboygan, Wis.

Filed June 9, 1971, Ser. No. 151,628

Term of patent 14 years

Int. Cl. D23—01

U.S. Cl. D23—40

Fig. 1

Fig. 2

FIG. 1 is a perspective view of a meter pit embodying my new design;

FIG. 2 is an elevational view taken from one side thereof, the opposite side being the same as the side shown and the bottom being open.

The bottom side is open.

I claim:

The ornamental design for a meter pit, substantially as shown and described.
